Otto A. Earl
ATTORNEY.

justed into alignment with the auxiliary rod or swung away from the window to a position in front of and substantially parallel to the portion thereof supported by the auxiliary rod.

It will be understood that I use the terms "main" and "auxiliary" in the specification and claims mainly for the purpose of convenience in description and in designating the parts.

I have illustrated and described the invention in a highly practical commercial embodiment thereof. I have not attempted to illustrate or describe other embodiments or adaptations of the invention and details in articulating the main rod to the bracket as it is believed that this disclosure will enable those skilled in the art to embody or adapt the invention as may be desired.

Having thus described my invention, what I claim as new and desire to secure by Letters Patent, is:

1. In a curtain or drapery fixture, the combination of a supporting bracket comprising a base member of channel section adapted for attachment to a support, longitudinally slotted main and auxiliary outer bracket members disposed within the channel of the base member in side by side relation and adjustably secured therein by a screw engaging the slots thereof, the auxiliary outer bracket member having a laterally disposed rod receiving arm, a main rod supporting link pivotally mounted on the outer end of the main outer bracket member, said main outer bracket member and link being provided with coacting stops limiting the swinging movement of the link relative to the bracket to approximately 90° from a position substantially at right angles to the bracket to a position substantially aligned therewith, a main rod supporting arm pivotally mounted on said link for swinging movement through approximately 90° from a position substantially in alignment therewith to a position substantially at right angles thereto, a main rod comprising telescoping sections, the inner of which is mounted on said main rod supporting arm for vertical tilting adjustment, and an auxiliary rod comprising telescoping sections, the inner of which has telescoping engagement with said arm of said auxiliary bracket member and the outer of which has an inturned outer end.

2. In a curtain or drapery fixture, the combination of a supporting bracket comprising a base member of channel section adapted for attachment to a support, longitudinally slotted main and auxiliary outer bracket members disposed within the channel of the base member in side by side relation and adjustably secured therein by a screw engaging the slots thereof, the auxiliary outer bracket member having a laterally disposed rod receiving arm, a main rod supporting link pivotally mounted on the outer end of the main outer bracket member, a main rod supporting arm pivotally mounted on said link, a main rod mounted on said main rod supporting arm, and an auxiliary rod mounted on said arm of said auxiliary bracket member.

3. In a curtain or drapery fixture, the combination of a supporting bracket having a laterally disposed rod receiving arm, a main rod supporting link pivotally mounted on said bracket, said bracket and link being provided with coacting stops limiting the swinging movement of the link relative to the bracket to approximately 90° from a position substantially at right angles to the bracket to a position substantially aligned therewith, a main rod supporting arm pivotally mounted on said link for swinging movement through approximately 90° from a position substantially in alignment therewith to a position substantially at right angles thereto, a main rod mounted on said main rod supporting arm, and an auxiliary rod mounted on said arm on said bracket, the main rod and said link being swingable relative to each other and to said bracket to position the main rod in substantially parallel relation to the auxiliary rod and at the front thereof or to position the main rod in alignment with the auxiliary rod.

EARL LIGHT.
